LINK CHAIN FOR A BRACELET OR SIMILAR ARTICLE

Max Hartmann, Warwick, R.I., assignor to Armbrust
Chain Company, Providence, R.I., a corporation of
Rhode Island

Filed Nov. 15, 1963, Ser. No. 77,447

Term of patent 14 years

(Cl. D45—4)

Fig. 1

Fig. 2

Fig. 3

Fig. 4

FIG. 1 is a front elevational view of a link chain for a bracelet or similar article showing my new design, said link chain having the identical appearance on its rear side;

FIG. 2 is a top edge view of a link chain for a bracelet or similar article showing my new design, said link chain having the identical appearance at its bottom edge;

FIG. 3 is a section taken on line 3—3 in FIG. 1; and

FIG. 4 is an end elevational view of one of the links per se.

Portions of the link chain are shown broken away to denote indeterminate length.

I claim:

The ornamental design for a link chain for a bracelet or similar article, substantially as shown and described.
